UNITED STATES PATENT OFFICE.

REGINALD C. STEEPLE, OF SPOKANE, WASHINGTON.

DESIGN FOR A FAN FIXTURE.

Application filed August 4, 1923. Serial No. 6,944. Term of patent 7 years.

To all whom it may concern:

Be it known that I, REGINALD C. STEEPLE, a citizen of the United States, residing at Spokane, in the county of Spokane and State of Washington, have invented a new, original, and ornamental Design for Fan Fixtures, of which the following is a specification, reference being had to the accompanying drawing, forming a part thereof, wherein:

I claim:

The ornamental design for a fan fixture, as shown.

REGINALD C. STEEPLE.
